J. E. LAMBETH,
CHAIR SEAT,
APPLICATION FILED NOV. 25, 1921.

1,411,635.

Patented Apr. 4, 1922.

Inventor:

James E. Lambeth,
Parker Cook.

Attorney

UNITED STATES PATENT OFFICE.

JAMES E. LAMBETH, OF THOMASVILLE, NORTH CAROLINA, ASSIGNOR TO THE STANDARD CHAIR COMPANY, OF THOMASVILLE, NORTH CAROLINA, A CORPORATION OF NORTH CAROLINA.

CHAIR SEAT.

1,411,635.

Specification of Letters Patent. Patented Apr. 4, 1922.

Application filed November 25, 1921. Serial No. 517,603.

To all whom it may concern:

Be it known that I, JAMES E. LAMBETH, a citizen of the United States of America, residing at Thomasville, in the county of Davidson and State of North Carolina, have invented certain new and useful Improvements in Chair Seats, of which the following is a specification.

My invention relates to a new and useful improvement in chair seats and has for an object to provide a seat that will be exceedingly strong and rigid in construction and so arranged and formed that it may be quickly and readily inserted in the body of the chair after the same has been assembled.

Still another object of the invention is to provide a detachable chair seat consisting of a rigidly assembled frame about which is completely woven a seating of rattan, cane, wicker or other fibre.

The usual practice of forming or constructing chairs that have a woven wicker or rattan seating is to assemble the chair body and place the same in a swinging frame and weave the seating directly around the side, front and rear stretchers. The chair has to be inverted from time to time and the weaving does not progress as rapidly as desired as the arms and legs, etc. impede the free movement of the operator.

With the present invention, however, a number of the chair seat frames, about to be described, can be assembled and around which can be easily and quickly woven the rattan seating as there are no outstanding parts to interfere with the action of the weaver.

Another disadvantage of the old style seat is, that when the seating is woven directly around the stretchers of the chair, and the seating becomes worn, new seating cannot be easily or readily substituted and the chair will be discarded even though the body of the same is in good condition.

With the present invention, however, should the seating become worn, the old seat frame may be quickly removed and a new frame with the seating thereon placed on the old stretchers. A few nails may be passed through the frame thus restoring the chair to a good condition, and at a nominal expense.

With the above and other objects in view the invention consists in certain new and

novel arrangements and combination of parts as will be hereinafter more fully described and pointed out in the claims.

Referring now to the drawings, showing a preferred form of the invention,

Fig. 1 is a perspective view of a conventional chair with my improved seat shown in position.

Fig. 2 is a plan view of the assembled seat frame,

Fig. 3 is a vertical edge of the same.

Fig. 4 is a fragmentary detailed perspective of one corner of the frame, a few of the strands of the seating being also shown.

Fig. 5 is a fragmentary detailed view showing the preferred form of weaving of the chair seat surface, and

Fig. 6 is a similar view of the preferred form of weaving of the bottom surface of the chair seat.

As clearly shown in Figs. 2 to 4 inclusive, the seat frame consists of the two side members or stretchers 1, which are cut away at their opposite ends to form the tongues 2, which tongues are adapted to tightly fit within the grooves 3, which grooves are formed in the transverse front and rear stretchers 4. The front stretcher is somewhat longer than the rear one so that the seat frame will taper from the front to the rear as clearly shown in Fig. 2.

Near the opposite end of each of these transverse stretchers an arcuate portion is removed as at 5 so that when the seat frame is placed in the chair 6 the periphery of the cut-out portions will partly encircle the uprights 7 of the chair, thus adding greatly to the rigidity of the entire chair.

The rattan or other seating which is in the form of strips 8 will be woven completely about the frame as shown in Fig. 1. The strands are made to pass over and under the separate members of the frame and may be woven to form the diagonal design shown as at 9. By so weaving the strands the surface of the seat will be relatively smooth and at the same time the diagonal configuration will tend to prevent any lateral or diagonal strains in the chair frame.

The bottom surface may be woven as shown at 10 as this surface does not have to be as smooth as the upper surface of the seat.

Of course, the seating may be woven in

any other desired configurations just so the strands completely encircle the frame of the seat.

It is a relatively simple matter to weave 5 the seating tightly about this seat frame and the tighter the weaving the more rigidly will the frame be held, which, of course, is greatly desired as the torsional and lateral strains on a chair seat will ordinarily soon 10 loosen the separate members of the frame and the chair body will lose the bracing effect of the seat frame.

After the frame has been assembled, as 15 shown in Fig. 2, a nail or dowel pin 11 may be passed through the tongue and groove portions to hold the members in their assembled position and after the seating has been applied to the frame the same may be placed in the chair, resting on the stretchers 20 12 of the chair, the periphery of the cut-out corners partly encircling the adjacent uprights of the chair body, thus tending to brace the body of the chair, and after being placed in position the frame, may be secured 25 to the stretchers with a few nails, not shown.

From the foregoing it will be seen that I have formed a seat frame that is exceedingly 30 strong and rigid in construction and at the same time so arranged that after it has been woven it may be quickly and readily placed in a new chair that is being assembled or may be quickly and readily substituted in a chair for an old seat which has been damaged by continual use.

35 Furthermore, much time can be saved in

weaving a detached seat frame rather than weaving the stretchers of the chair and a much more rigid frame is secured as the tighter the weaving the tighter the parts of the frame will be held together.

Also, new seats can be readily replaced 40 which often times will save the discarding of the entire chair body.

Of course, different size frames may be made according to the different style chairs 45 manufactured and I do not wish to be limited in any way to the style of chair shown as it is simply a conventional one and shown for the purpose of illustration.

Many slight changes may be made without 50 in any way departing from the spirit and scope of the invention.

Having thus described the invention what I claim as new and desire to secure by Letters Patent is:

A detachable chair seat comprising a 55 frame having front, side and rear stretchers, said front and rear stretchers having portions near their ends cut away to form projections, said projections provided with 60 grooves, the side stretchers provided with tongues fitting within said grooves, a seating woven completely around the frame 65 tightly holding the frame in its assembled position, the cut out portion of the front and rear stretchers being arcuate and adapted to partly encircle the uprights of the chair.

In testimony whereof I affix my signature.

JAMES E. LAMBETH.
